UNITED STATES PATENT OFFICE

2,465,347

RECOVERY OF SUGAR PRECURSORS

Robert M. Boehm, Laurel, Miss., and Horace E. Hall, Lyle, Tenn., assignors to Masonite Corporation, Laurel, Miss., a corporation of Delaware

No Drawing. Application March 31, 1944.
Serial No. 529,034

8 Claims. (Cl. 127—40)

1

This invention relates to separation of non-cellulosic carbohydrate anhydrides, or sugar precursors, i. e., materials from which sugars may be formed, from solutions thereof in water, which may also contain other materials, such as sugars, tars, etc., in solution or suspension.

Two illustrative embodiments of the invention will be described. First is the practice of the process upon wood liquors derived from wood or woody ligno-cellulose materials, which may be obtained, as by expression or washing, from fiber produced by subjecting wood chips to the hydrolyzing action of high pressure steam in a gun, such as described in U. S. Patent 1,824,221 to Mason, followed by explosive discharge from the gun. Such a liquor is described in U. S. Patent No. 2,224,135 to Boehm.

In accordance with the description contained in the latter patent, lignocellulose material in the form of coarsely divided chips is subjected to saturated steam at pressures of about 600 to 1000 pounds per square inch and at corresponding temperatures (252° C. to 285° C.) in a gun for a short period of time. As a result of the hydrolysis treatment, the water soluble materials are increased and the liquor thus obtained from the hydrolysis treatment is used as the starting material in the present invention.

The wood liquor obtained as described contains materials produced from the hemicellulosic materials of the wood by the high pressure steam treatment, and which are soluble or dispersible in water. From these materials hexose and pentose sugars may be formed, and while such precursors of hexose and pentose may be in part polyuronides as well as polysans, they are herein referred to for convenience as hexosans and pentosans. The liquor also contains soluble or dispersed tars, some free sugars, acetic acid, formic acid, soluble or dispersed lignin or lignin degradation products, astringents and other materials, the removal whereof is desirable in order to secure the sugar precursors in relatively pure form. The solid content of wood liquor obtained as above described may be about 5% to 10%. It is preferably concentrated to about 15%—50% of solid content before treatment according to this invention, and about 25% is preferable.

The invention can also be made use of in a second embodiment for recovery of sugar precursors such as hexosans by precipitation from water solutions containing same along with sugars such as pentoses and substantially free from other materials. By applying the process of the present invention to such mixed solutions, the sugar precursors may be precipitated and removed and thus separated from the free sugars, such as pentoses and hexoses, which remain in solution.

The principal object of the invention consists in the provision of a process whereby the sugar

2

precursors are precipitated so that they can be separated in relatively pure form by adding to the liquor certain oxygenated organic water-miscible liquid materials, which are of such nature that the sugar precursors are precipitated because they are insoluble in the mixture of the added material with the water of the liquor.

A further object is the provision of a process whereby sugar precursors can be separated from free sugars. Additional objects of the invention will appear in connection with the further description.

The preferred material to be admixed with the liquor to be treated consists of a mixture of about 4 parts of acetone with one part of isopropyl ether. While mixtures containing from about 3 to 8 parts of acetone to one part of isopropyl ether may be used, the 4 to 1 ratio gives best results. Straight acetone may also be used when rapid precipitation is not important. Dioxane may also be used, or lower aliphatic alcohols, such as methanol or ethanol. Upon making the addition, the materials are preferably thoroughly stirred or agitated. It is believed that a dehydration of the sugar precursors is effected by the described treatment, but at any rate the sugar precursors are insoluble in the mixture and are precipitated in substantially pure state, and the additive materials used to effect the precipitation will be designated precipitating agents.

Precipitating agent material may be added in amount of approximately 2-7 times the quantity of the solutions to be treated, but about 4 times gives best results and is preferred.

The precipitate of sugar precursors, which is white or light brown, can be separated from any materials remaining in solution, as by filtration.

Best results and highest purity of yield of sugar precursors are obtained by adjusting the pH of the solution to about 5.5. However, a range of pH from about 2-11 is permissible.

In one case, using the preferred precipitating agent material, namely 4 parts of acetone to 1 part of isopropyl ether, and the preferred ratio of the precipitating agent material to liquor, namely 4 parts thereof to 1 part of liquor, such liquor containing about 25% of solid materials, and having a pH of 5.5, the per cent recovery of sugar precursors by precipitation was 97.4, and the per cent purity of such recovered sugar precursors was 86.7.

The precipitation can be accelerated by the use of a minor proportion of an electrolyte, preferably an electrolytic salt, such as about 1%—5% of aluminum sulfate on weight of solution.

The tars and other materials present in the wood liquor will remain in solution or suspension. Should some of these materials be carried down with the sugar precursor material, the separated precipitate may be washed with acetone or the like material for their removal.

As already stated, solutions containing sugar precursors such as hexosans and also containing sugars such as pentose sugars and substantially free from other materials may be treated to separate the hexosans from the pentose sugars by making use of the present invention.

One way to secure such a solution, i. e., a solution containing hexosans and pentoses, from the precipitated sugar precursors obtained from wood liquors as above described consists in putting such precipitated sugar precursors into solution in water, and subjecting same to enzymatic hydrolysis by means of *Aspergillus Niger* enzyme material.

By such enzymatic hydrolysis, the pentosans are converted to pentose sugars, while the hexosans remain substantially unchanged, and after the hydrolysis, both of these are in solution in the water. A practically clear solution can be obtained after filtering out the inoculated bran or the like used for introduction of the enzyme material, etc.

Upon the addition to such a solution of the acetone-1 isopropyl ether mixture, or other additive material as already described, the hexosans are precipitated, and can be removed in relatively pure state, while the pentose sugars remain in solution. Thus the hexosan material is separated from the pentose sugar, and each may be utilized as desired.

The enzymatic hydrolysis treatment above referred to is not per se a part of this invention, being described and claimed in the copending application of Horace E. Hall and Lester L. Coleman, Serial No. 529,037, filed March 31, 1944, now Patent Number 2,444,823, dated July 6, 1948.

We claim:

1. Process of preparing pentosans and hexosans from a fibrous lignocellulose material which comprises subjecting fibrous lignocellulose material in coarsely divided state to a hydrolyzing action with saturated steam at pressure of approximately 600-1000 pounds per square inch and corresponding temperatures whereby a substantial part of said material is converted to water solubles in the form of pentosans and hexosans, separating the pentosans and hexosans from the hydrolyzed lignocellulose material by treating the hydrolyzed material with water, mixing with the pentosans and hexosans water solution water miscible organic compound containing at least one compound selected from the group consisting of acetone, ethers, and lower aliphatic alcohols in quantities ranging from 2 to 7 times the quantity of the water solution to precipitate the pentosans and hexosans from the solution, and removing the precipitate from the solution.

2. Process as in claim 1, and in which the precipitation of the pentosans and hexosans is accelerated by the addition of an electrolyte to the water solution of pentosans and hexosans.

3. Process as in claim 1, and in which the precipitation of the pentosans and hexosans is accelerated by addition to the water solution of pentosans and hexosans of about 1% to 5% aluminum sulfate based on the weight of the solution.

4. Process as in claim 1, and in which the additive precipitating material is about 4 times the quantity of the water solution.

5. Process as in claim 1, and in which the pH of the pentosan and hexosan water solution is adjusted to about 5.5 before addition of the precipitating material to the solution.

6. Process of preparing pentosans and hexosans from fibrous lignocellulose material which

comprises subjecting fibrous ligno-cellulose material in coarsely divided state to a hydrolyzing action with saturated steam at pressure of approximately 600 to 1000 pounds per square inch and corresponding temperatures whereby a substantial part of said material is converted to water solubles in the form of pentosans and hexosans, separating the pentosans and hexosans from the hydrolyzed ligno-cellulose material by treating the hydrolyzed material with water, mixing with the pentosan and hexosan water solution a mixture containing 3 to 8 parts acetone and one part isopropyl ether in quantities ranging from 2 to 7 times the quantity of the water solution to precipitate the pentosans and hexosans from the solution, and removing the precipitate from the solution.

7. Process of preparing pentosans and hexosans from fibrous ligno-cellulose material which comprises subjecting fibrous ligno-cellulose material in coarsely divided state to a hydrolyzing action with saturated steam at pressure of approximately 600 to 1000 pounds per square inch and corresponding temperatures whereby a substantial part of said material is converted to water solubles in the form of pentosans and hexosans, separating the pentosans and hexosans from the hydrolyzed ligno-cellulose material by treating the hydrolyzed material with water, mixing with the pentosan and hexosan water solution methanol in quantities ranging from 2 to 7 times the quantity of the water solution to precipitate the pentosans and hexosans from the solution, and removing the precipitate from the solution.

8. Process of preparing pentosans and hexosans from fibrous ligno-cellulose material which comprises subjecting fibrous ligno-cellulose material in coarsely divided state to a hydrolyzing action with saturated steam at pressure of approximately 600 to 1000 pounds per square inch and corresponding temperatures whereby a substantial part of said material is converted to water solubles in the form of pentosans and hexosans, separating the pentosans and hexosans from the hydrolyzed ligno-cellulose material by treating the hydrolyzed material with water, mixing with the pentosan and hexosan water solution dioxane in quantities ranging from 2 to 7 times the quantity of the water solution to precipitate the pentosans and hexosans from the solution, and removing the precipitate from the solution.
